UNITED STATES PATENT OFFICE.

ELMOND C. IMMEL, OF CISCO, TEXAS, ASSIGNOR OF ONE-HALF TO EDWARD T. MURRAY,
OF EASTLAND, TEXAS.

CASING SPEAR.

Application filed September 6, 1922. Serial No. 526,527.

To all whom it may concern:

Be it known that I, ELMOND C. IMMEL, a citizen of the United States, residing at Cisco, in the county of Eastland and State of Texas, have invented certain new and useful Improvements in Casing Spears, of which the following is a specification, reference being had to the accompanying drawings.

The present form of spear is a tool employed for fishing or pulling pipes and casings from wells, and the hereinafter specified tool is of the "bull dog" type, and a purpose of this invention is to provide a very simple, efficient and practical construction of tool, wherein the slips are mounted so as to gravitate, in order to expand against and grip the inner surface of a casing or pipe, whereby it may be extracted or pulled from a well.

One of the tools of this character heretofore employed includes spring rings, to hold the slips of the spear together, and furthermore this type of tool is more or less complicated, though it is considered one of the best tools now in use. Furthermore it has been found that this character of tool has on several occasions caused a bad fishing job, when extracting or pulling casings or pipes from wells.

It is, therefore, another purpose to provide a casing spear, wherein these disadvantages are overcome, not only due to the fact that the upper and lower ends of the slips are retained in position against loss, but also due to the fact that the slips are independently movable, so that they may assume different positions, when they fall or drop by gravity into gripping positions.

Still another purpose is the provision of a "bull dog" type of casing spear, wherein the slips cannot be removed whether expanded or contracted, and also wherein the telescoping ends of the slips are sufficiently strong to withstand any strain, to which they may be subjected.

A further purpose is the provision of a casing spear constructed to guarantee absolute freedom of action either up or down, as they are not in any way held in position by a spring or any contrivance whatever. It has been found that the present form of spear has the advantage over others, due to the fact that it will take a more perfect hold on the inner surface of the casing or pipe, as the

slips are capable of movement either independently or together. 55

In the type of tool as heretofore employed, this feature is not present, for the reason that the slips in such type of tool are held together by means of a spring ring, which forces all the slips to work up and down together, and not independently. 60

It is to be understood that the particulars herein given are in no way limitative and that while still keeping within the scope of the invention, any desired modifications of detail and desired proportions may be made in the apparatus according to circumstances. 65

The invention comprises further features and combination of parts, as will be herein-after set forth, shown in the drawings and claimed. 70

In the drawings:—

Figure 1 is a view in elevation, showing the improved casing spear lowered into a casing or pipe, showing the slips engaging the inner surface of the pipe; 75

Figure 2 is a vertical sectional view through the casing spear, showing the construction of the various parts; 80

Figure 3 is a cross sectional view on line 3—3 of Figure 2; 85

Figure 4 is an enlarged detail view of the body member of the tool, showing the conical spindle of the device; 90

Figure 5 is a detail perspective view of one of the slips. 95

Referring to the drawings, 1 designates the body of the tool, the upper end of which has a conical extension 2 provided with exterior threads 3, for connection with a suitable member, whereby the casing spear may be lowered into a well, for the purpose of extracting a casing or pipe. The other end of the body 1 has a reduced portion 3^a, which is also exteriorly threaded, for the engagement of the threads 4 on the interior of the collar 5. 100

Projecting from the reduced portion 3^a and extending axially is a spindle 6, which is conical. In fact this spindle gradually tapers from its lower end, to a point adjacent where it forms an integral part of the reduced portion 3^a. The larger end of the conical spindle 6 has a reduced threaded extension 7, which engages the interior threads 8 of the nose casing 9. The extreme nose of this nose casing is frustro-conical, so as

2
to easily enter the casing or pipe to be extracted from the well.

Engaging the surface of the conical spindle 6 are slips 10. These slips conform to the shape of the spindle 6, and are capable of movement on the spindle, that is to say sliding movements. The upper and lower ends of these slips are reduced on their exterior surfaces, and those portions between 10 the reduced exterior surfaces of the ends of the slips are exteriorly threaded as shown at 12. These threads 12 are pitched in upwardly and lateral directions, so that when the slips lower on the spindle, and thereby become expanded, the threads will bite into the inner surface of the pipe or casing, and insure sufficient grip, whereby the casing or pipe may be extracted from the well.

The nose casing adjacent the larger end 20 of the spindle 6 is chambered or reamed out as shown, in order to provide a chamber 13 for the reception of the exterior unobstructed smooth surfaces of the reduced ends of the slips, thereby retaining the slips in position.

The collar 5, which engages the threads on the reduced portion 3^a of the body also has its interior for half its depth reamed or chambered out, to provide a chamber 14, which receives the upper reduced ends of the slips.

When extracting or fishing a pipe or casing from a well, a member (not shown) may be connected to the tapered extension 2. The casing spear is then lowered into the well until the spear enters the pipe or casing to be extracted. Obviously when the casing spear is being lowered into the well, for the purpose of fishing or extracting the pipe or casing from the well, the slips automatically drop or fall by gravity, until the lower reduced ends of the slips enter the chamber of the nose. The slips become limited in these movements, just as soon as the threaded surfaces of the slips contact with the inner circumference of the casing or pipe. As an upward pull is imparted to the member to which the spear is connected when lowered into the well, the spindle due to its gradual taper, forces or expands the slips outwardly, to insure a biting engagement of the threads of the slips with the interior surface of the casing or pipe to be extracted. When a secure gripping action is effected, still further upward movements may be imparted to the member which carries the spear, thereby permitting the pipe or casing to be easily removed from the well. Obviously when the casing spear is not in use, the slips may move 60 in an opposite direction, as soon as the spear is inverted, or in other words as soon as the nose of the spear is directed upwardly, instead of downwardly. The present form of casing spear can be used on the interior of 65 any size of pipe or casing from two inches

upward, according to the requirement. Furthermore one body can be used for more than one or two sizes of slips, so that different sizes of casings or pipes can be extracted. In other words the casing spear can be made in different sizes, and due to the fact that the slips can be constructed to afford a greater diameter of gripping surface, casings and pipes of various diameters may be extracted from wells.

The invention having been set forth, what is claimed is:—

1. In a casing spear, the combination with a body provided with a depending axially aligned spindle, said spindle being tapered from its lower end upwardly to the body, a plurality of slips engaging the surface of the tapered spindle, said slips being independently movable by gravity and having upper and lower reduced ends, and means mounted upon the body adjacent the upper and lower ends of the slips and receiving said ends, thereby retaining the slips in position, and yet permitting them to move by gravity into gripping position.

2. In a casing spear, a spear body comprising a spindle tapered from its lower end upwardly, segmental slips in surrounding relation to the spindle, and being movable by gravity, and means adjacent the upper and lower ends of the slips and operatively engaging said ends, to guide the slips in their expanding actions, the exterior of the slips provided with means for insuring a gripping action upon the interior of a casing or pipe when the slips are expanded.

3. In a casing spear, a body having a spindle conically reduced from its lower end upwardly, a plurality of segmental slips engaging said conical spindle, whereby upon lowering said slips by gravity they become expanded for gripping action with the interior of a pipe to be extracted, and means for operatively receiving and retaining the upper and lower ends of the slips in position, whereby they are guided, as they are lowered.

4. In a casing spear, a body, a collar having a chambered out end threaded adjustably upon one end of said body, a spindle projecting from one end of the body and being conically reduced from its lower end upwardly to where the spindle axially connects with the body, a nose casing threaded upon the lower end of said spindle, said nose casing being provided with a chamber, said chambers receiving the upper and lower reduced ends of the slips to anchor the slips in place, and yet permit them to move by gravity to lowered positions, the exterior surfaces of the slips having means for gripping the inner circumference of a casing or pipe to be extracted.

In testimony whereof I hereunto affix my signature.

ELMOND C. IMMEL.
